UNITED STATES PATENT OFFICE.

JESSE FERGUSON, OF HOYTVILLE, OHIO.

BALLOT BOX.

Application filed December 28, 1926. Serial No. 157,595.

The present invention is directed to improvements in ballot boxes for voting precincts.

The primary object of the invention is to provide a device of this kind so constructed that it can be locked effectively to prevent unauthorized persons from having access thereto.

Another object of the invention is to provide a ballot box which is extremely simple in construction and one in which the same locks employed for locking the covers of the ballot and stub compartments can be used for maintaining the respective covers in unlocked position.

Another object of the invention is to provide a ballot box divided into compartments so arranged that the ballots can be deposited in a designated compartment and the stubs of the ballots deposited in an adjacent compartment in order that the judges of election can, at the closing of the polls, check the ballots and stubs in a convenient manner.

In the accompanying drawings:

Figure 1 is a perspective view of the device.

Figure 2 is a sectional view on line 2—2 of Figure 1.

Figure 3 is a sectional view on line 3—3 of Figure 2.

The box is designated generally by the numeral 1 and consists of a bottom 1, end walls 2, and front and rear walls 3 and 4, respectively. Corner posts 5 are provided and have their lower ends terminating in legs 6, said legs being equipped with casters 7 to permit the box to be conveniently rolled over a floor.

Extending from the front and rear walls 3 and 4 are partitions 8 dividing the box into compartments 9, 10, 11, 12, 13 and 14, the compartments 9, 11 and 13 being for the purpose of receiving the ballot stubs, the capacity of which being less than that of the remaining compartments. The compartments 10, 12 and 14 are for the reception of ballots which, being greater in bulk, require more space than necessary for the stubs. I have illustrated a box divided into six compartments, but it will be of course understood that the number may be increased, as desired.

Secured to the upper edges of the parti-

tions 8 and end walls 5 are strips 15 provided with grooves 16 to provide guides for the covers 17 of the respective compartments.

These covers are provided adjacent their rear ends with transverse slots 18, through which the ballots and stubs are passed to their respective compartments. Also carried by the covers 17 and disposed rearwardly of the slots are stands 19, the ones adjacent the slots of the covers for the compartments 9, 11 and 13 bearing the designations "Stubs", while the remaining stands have thereon such indicia as "Judicial ticket", "County ticket" and "State ticket". This indicia may form a permanent part of the stand, or may be in the nature of a removable card.

Secured upon the upper edges of the front and rear walls 3 and 4 are strips 20 and 21, respectively.

The covers 17 have fixed to their rear ends plates 22 provided with perforations 23 and mated therewith and fixed to the strips 21 are plates 24, the perforations 25 thereof being adapted to register with the perforations 23 and at which time are in position to receive the shackles 26 of the locks 27. In this manner the covers are locked and access to the compartments by unauthorized persons prevented. It is also desired at times to prevent the covers from being locked and to accomplish this the shackles of the locks are engaged in the perforations of the plates 22 and secured, as indicated by dotted lines in Figure 3 of the drawings, it being obvious that when these conditions prevail the presence of the shackles in the perforations 23 will prevent the same from being placed in registration with the perforations 25. In this manner the covers can not be locked by an unauthorized person.

Secured to the under surface of the covers 17 adjacent their forward ends are transverse cleats 27 having secured thereto clips 28 adapted to engage under the strip 20, as shown in Figure 3 of the drawings. These clips obviously stabilize the covers, while the cleats prevent withdrawal of the covers and limit the rearward sliding movement thereof due to the fact that they will engage the strip 21 when open.

From the foregoing description, it will be seen that a ballot box has been provided and

is constructed in such manner that fraudulent access to the ballots deposited therein is positively prevented.

Having thus described the invention, I claim:

A ballot box having partitions disposed therein to provide independent ballot and stub receiving compartments having open upper ends, covers slidably mounted for

closing the open ends, said covers and box having plates fixed thereto and provided with perforations adapted to register, and means engaged in the perforations for interlocking the plates to lock the covers in their closed positions.

In testimony whereof I affix my signature.

JESSE FERGUSON. [L.S.]
